UNITED STATES PATENT OFFICE.

CARL GUSTAV SCHIMKAT, OF FREMONT, OHIO, ASSIGNOR TO ILLINOIS CUTLERY COMPANY, OF BLUE ISLAND, ILLINOIS, A CORPORATION.

SAFETY-RAZOR.

936,045.

Specification of Letters Patent.

Patented Oct. 5, 1909.

Application filed October 21, 1908. Serial No. 458,765.

To all whom it may concern:

Be it known that I, CARL GUSTAV SCHIMKAT, a citizen of the United States, residing at Fremont, in the county of Sandusky, 5 State of Ohio, have invented certain new and useful Improvements in Safety-Razors; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to razors of the safety type, wherein a thin blade is movably held in position with its cutting edge adjacent a guard which projects beyond the edge of the blade to prevent cutting the face, 20 it being customary to furnish with razors of this type a number of blades so that when a blade becomes dull, a sharp blade may be quickly substituted therefor; and the invention consists in the construction and arrangement of parts hereinafter more fully 25 set forth and claimed.

The primary object of the invention is to produce a razor of the character described, of 30 comparatively simple and inexpensive construction, wherein the arrangement is such as to enable a blade having two cutting edges to be supported in a manner to render it adaptable for use, and at the same time enable the blade to be easily inserted and 35 quickly removed.

A further object is to provide means for supporting a blade having two cutting edges without injury to the cutting portion of either edge of the blade, and in a manner to 40 enable the blade to be readily handled for insertion and removal without danger of cutting the hand.

A further object is to provide a holder for the blade of such construction that the blade 45 shall be supported at its ends only, the intervening portion of the frame between the supporting ends which carries the guard teeth, being depressed so as to afford a space between the edge of the blade and the guard 50 for the passage of hair and lather, the blades employed being sufficiently rigid to render them operative for shaving without any support except at their extreme ends.

A further object is to provide means for 55 positioning the blade in the holder and

maintaining the cutting edge thereof always straight with the guard.

A further object is to provide means for holding the blade yieldingly in place with sufficient force to prevent movement of the 60 blade during the operation of shaving.

The above objects are attained by the structure illustrated in the accompanying drawings, in which:—

Figure 1 is a front elevation of a razor 65 embodying my invention, showing the blade in position. Fig. 2 is a side elevation thereof. Fig. 3 is an enlarged sectional view through the blade, the supporting-plate or frame and the guard, as on line 3—3 of Fig. 70 1. Fig. 4 is a top plan view of Fig. 1. Fig. 5 is a similar view showing the position of parts during the operation of removing or inserting a blade. Fig. 6 is a top plan of the blade-supporting plate with the blade removed. Fig. 7 is a perspective view of the 75 spring which is mounted on the back of the supporting-plate or frame and carries on its ends the angle brackets which engage the rear corners of the blade and through the 80 tension of the spring force the forward edge of the blade against the stop lugs on the end portions of the spring frame. Fig. 8 is a 85 rear elevation of the razor. Fig. 9 is an end elevation of the blade. Fig. 10 is a longitudinal section as on line 10—10 of Fig. 4.

Referring to the characters of reference, 1 designates the handle, of any suitable construction, having a reduced threaded stem 2. The frame or blade-holding plate 3 is 90 oblong and quadrangular in form, having a depending back portion 4 terminating in a reduced forwardly extending part 5 which is provided with a tapped aperture to receive the threaded stem of the handle, where- 95 by the supporting-plate may be detachably mounted on the handle, as shown. The central portion of the supporting-plate is de- 100 pressed, as shown at 6, leaving the end por- 105 tions 7 of said plate above the plane of said depressed portion. The forward edge of the depressed portion of the plate between the supporting end portions 7, is provided with a plurality of teeth or downwardly curved fingers 8 which form a guard that prevents the edge of the blade cutting the face, as will be well understood in the art. By de- 110 pressing the guard portion of the supporting-plate between the end portions 7 thereof, a space 9 (see Fig. 3) is formed between the

guard and the edge of the blade 10 when said blade is in position for shaving, affording a free passage for the hair and lather and preventing the clogging of the lather 5 between the guard and the edge of the blade, a result common in razors of this type where the blade rests directly upon the guard. An accumulation of lather between the teeth of the guard and the edge of the blade holds 10 the blade from contact with the face and renders the razor inoperative until said accumulation is removed.

Upon the end portions 7 of the supporting-plate at their outer edges are formed the 15 stop lugs 11 under which the forward edge of the blade at the corners is adapted to engage, whereby the blade is caused to stand in alinement with the guard and is held in proper relation thereto. For the purpose of 20 pushing the forward edge of the blade against the stop lugs 11, a spring arm 12 is employed having the centrally depending ear 13 which is riveted or otherwise fastened to the back 4 of the supporting-plate. Said 25 spring arm extends transversely across the back of the supporting-plate and its end portions are curved forwardly, as shown at 14. Each of the forwardly curved end portions of said spring is provided with a vertically 30 extending corner bracket 15. Said brackets lie in the right-angle recesses 16 formed by cutting away the rear corners of the supporting-plate and extend above the plane of said plate, as shown. The shape 35 of said brackets is such as to cause them to embrace the rear corners of the blade when said blade is placed upon the supporting-plate, whereby the blade may be held only at its corners, and at the same time 40 properly positioned longitudinally. The distance between the stop lugs 11 and the brackets 15 is less than the width of the blade, so that to place the blade in the holder its rear corners are caused to engage in said 45 brackets, when by applying a rearward pressure to the blade, the spring arm 12 will yield sufficiently to allow the forward corners of the blade to engage under the stop lugs 11, when by releasing the blade, the tension 50 of said spring arm will crowd it forward against said lugs and hold it with sufficient tension to maintain it in place during the operation of shaving. It will be noted that the stop lugs and the spring supported brackets engage the blade only at the 55 corners so that the cutting edges of the blade are not dulled or injured by the means which holds the blade in place.

In manipulating the blade for the purpose 60 of inserting it in or removing it from the frame or holder, it is grasped at the ends between the thumb and finger, the end portions of the holder or supporting-plate being concaved, as shown at 17 in Fig. 6, to facilitate the handling of the blade in the manner 65

stated. By this arrangement, a blade with parallel cutting edges may be readily held in a manner to enable the blade to be easily reversed when one edge becomes dull, thereby rendering the blade doubly serviceable 70 with comparatively little additional expense, the arrangement for holding the blade being simple and inexpensive and of a character to prevent injury to the edge not in use while said blade is being held in operative 75 position in the holder. The pressure exerted by the end portions of the spring arms against the rear corners of the blade is such as to crowd the blade forward against the stop lugs, thereby obviating the possibility 80 of the cutting edge of the blade being held at an angle to the guard, and insuring a perfect positioning of the blade under all conditions.

Having thus fully set forth my invention, 85 what I claim as new and desire to secure by Letters Patent, is:—

1. In a razor, the combination of a blade-holding member having a guard along one edge, a blade having parallel cutting edges, 90 stops upon the blade-holding member adapted to engage the forward corners of the blade for alining said blade with respect to said guard, a spring arm mounted on the back of the blade-holding member having 95 brackets at its ends to engage the rear corners only of said blade and press the blade forward against said stops, said brackets having engagement also with the ends of the blade to prevent longitudinal movement 100 thereof on the blade-holding member.

2. In a razor, the combination of a blade-holding member having an immovable guard along one edge, a blade having parallel cutting edges, the blade-holding member having stops at its forward edge to engage the front edge of the blade at its corners only and aline said blade with respect to said guard, a spring arm fastened at its center to the back of the blade-holding member 105 the free ends of said arm being formed to engage the rear corners only of the blade and carry the forward corners thereof against said stops, said engaging ends of said arm preventing longitudinal movement 110 of the blade while carrying said blade into operative position.

3. In a razor, the combination of a rigid blade-holding member, a blade having parallel cutting edges, the blade-holding member having fixed stops at its forward corners to engage the forward corners of the blade, a spring arm mounted upon the rear portion of the blade-holding member engaging at its ends the rear corners of the blade only for urging the blade laterally against said stops and preventing longitudinal movement thereof.

4. In a razor, the combination of a blade-holding member having fixed blade-engag- 139

ing stops at its front corners and a fixed guard along its front edge, a spring member fixed on the blade-holding member having resilient end portions, said resilient end portions of said spring member having angular corner brackets to engage the rear corners only of the blade and carry the blade transversely of the blade-holding member to cause engagement of its forward cor-

ners with said stops in alinement with the 10 fixed guard and prevent longitudinal movement of said blade.

In testimony whereof, I sign this specification in the presence of two witnesses.

GUSTAV SCHIMKAT.
